DESIGN FOR AN ALPHABET FOR FORMING MONOGRAMS OR THE LIKE

Michael Chernow, Brooklyn, N. Y., assignor to
Service Patents Corporation, a corporation of
New York

Application March 27, 1935, Serial No. 56,078

Term of patent 7 years

To all whom it may concern:

Be it known that I, Michael Chernow, a citizen of the United States and residing at Brooklyn, in the county of Kings and State of New York, have invented a new, original, and ornamental Design for an Alphabet for Forming Monograms or the like, of which the following is a specification, reference being had to the accompanying drawing, forming part thereof, and in which

Fig. 1 is a view of the alphabet showing my new design, and

Fig. 2 is a perspective view showing one of the letters of the alphabet.

Each character of the alphabet is a block of substantial thickness thinned at its upper and lower edges by a succession of rectangular steps.

I claim:

The ornamental design for an alphabet for forming monograms or the like, substantially as shown and described.

MICHAEL CHERNOW.
